UNITED STATES PATENT OFFICE.

HALVER R. STRAIGHT, OF ADEL, IOWA.

VENTILATED BUILDING STRUCTURE.

1,316,982.

Specification of Letters Patent. Patented Sept. 23, 1919.

Application filed May 15, 1916. Serial No. 97,755.

To all whom it may concern:

Be it known that I, HALVER R. STRAIGHT, a citizen of the United States, and resident of Adel, in the county of Dallas and State 5 of Iowa, have invented a certain new and useful Ventilated Building Structure, of which the following is a specification.

My improvement relates to that class of 10 ventilated building structures which is preferably made of hollow clay tile, for the purpose of forming corn cribs or the like.

In a former application I have illustrated and described such a structure as applied to 15 a circular hollow tile corn crib, which application may be identified as Serial Number 735,856, filed December 9, 1912, and now issued as Patent No. 1,154,219 under date of September 21, 1915.

In many instances it is desirable to have 20 these ventilated building structures made in rectangular form instead of round, and obviously the method employed in my said round structure cannot be used to advantage in a rectangular structure.

25 The object of my present invention is to devise a means whereby hollow tile may be employed in the erection of a rectangular structure for corn cribs or similar purposes, in which some of the solid upright columns 30 thereof may be formed of the same hollow tile that are employed in the body portion of the wall with the openings thereof arranged to run vertically for the reception of bracing rods, the vertical spaces thereof 35 around the rods being designed to receive concrete for the purpose of sealing the rods and bracing the whole structure to form a rigid upright column to which binding wires or rods may be applied for holding the walls 40 between the rigid upright columns.

A further object is to provide improved 45 means for resisting the outward thrust upon the straight portions of the wall between the rigid upright columns, which means are of simple and inexpensive construction that may be readily and quickly laid in place by ordinary workmen.

50 My invention consists in the construction, arrangement and combination of the various parts of the device, whereby the objects contemplated are attained, as hereinafter more fully set forth, pointed out in my claims and illustrated in the accompanying drawings, in which:

55 Figure 1 shows a horizontal, sectional view through a part of a rectangular masonry structure embodying my invention.

Fig. 2 shows a vertical, sectional view, the lower part of the figure showing a side elevation of a building embodying my invention, and the upper part a sectional view on the line 2-2 of Fig. 1.

Fig. 3 shows an enlarged detail, vertical, sectional view on the line 3-3 of Fig. 1.

Fig. 4 shows a similar view taken at right angles to that on which Fig. 3 is taken, and

Fig. 5 shows a detail, perspective view of one of the hollow tile building blocks from which my improved structure is built.

Referring to the accompanying drawings, 70 the building blocks employed in my improved structure are of the kind illustrated in Fig. 5, and may be made in an ordinary tile making machine by being forced through a suitable die. In cross-section it is 75 preferably square and comprises a body portion 10 having a vertical central web 11 and a horizontal central web 12. The ends of the block, however, are beveled or inclined both in the same direction so that 80 when the block is laid flat the ends thereof incline upwardly and laterally both in the same direction at an angle of about twenty degrees from the vertical.

In erecting a building according to my 85 improvement and with hollow tile blocks of the character described, I first provide a suitable base 13 which may be made of concrete. At the corners of the base I place vertically arranged reinforcing rods 15 and 90 at suitable intervals throughout the side walls I place a number of vertically arranged reinforcing rods 16. I then place a layer of the hollow tile blocks on the base with the ends thereof exactly vertical so that the tops and bottoms thereof 95 incline downwardly and outwardly, as shown at the upper right side of Fig. 2.

At the center of the side wall I place the 100 hollow tile blocks in position with the openings extending vertically and slip them down over the rods 16. On the bottom layer for instance, I provide a single block with the openings vertical and with the rods 16 extended through said openings, then on the second layer I provide two of these blocks arranged with the openings vertical and with the rods 16 running through the adjacent vertical openings of the two blocks, 105 as clearly illustrated at the central top portion of Fig. 2. Between each horizontal row of blocks thus laid I provide one or more reinforcing rods. These rods are secured at their ends to the upright rods 15 at the 110

- corner posts. Then they are laid on top of the downwardly and outwardly inclined blocks and are extended on the inner sides of rods 16 and so on around the building. 5 These reinforcing rods are curved so that between a center rigid post and a corner rigid post the central portion of the reinforcing rod will lie near the outer edge of the building blocks, while at the center rigid 10 upright and at the adjacent corner rigid upright the rod comes near to the inner face of the wall. These rods are laid in a layer of concrete 17 between each of the horizontal rows of building blocks.
- 15 After a wall has been built up to a certain predetermined height the blocks which surround the rods 16 are poured full of concrete and allowed to set and harden and the corner posts are completed by surrounding the upright rods 15 with a solid body of concrete.
- 20

By my improved structure a comparatively large and high ventilated corn crib may be built in a strong and durable manner by means of very cheap and inexpensive material, the blocks of which may be made on an ordinary tile making machine and the wall may be made very thin. The openings in the wall all incline downwardly 25 and outwardly. This gives to the incoming air the proper upward direction of circulation and at the same time it permits rain or snow driven against the wall to drain outwardly and downwardly thereby preventing it from entering the interior of the 30 crib or structure.

My improved method of erecting a central rigid supporting base for a building wall has a number of advantages in that it 40 may be very quickly and easily erected by ordinary workmen out of cheap and inexpensive materials, and then after being erected may be filled with plastic concrete and permitted to set and harden.

45 Another advantage is that all of the metal parts of the structure are embedded in and covered with concrete and thus are prevented from rusting or corroding.

In order to withstand the successive pressures in an outward direction in a ventilated wall of this kind, such as occur in a 50 rectangular building intended to hold corn or the like, it is necessary that the reinforcing wires or rods be so arranged that they 55 cannot move outwardly simply by bending as would be the case if it were attempted to use straight reinforcing rods between the layers of tile. By my improved arrangement the horizontal reinforcing rods form 60 a truss and by having these rods extended outwardly to a point near the outer edge at the central point between the two rigid up-

rights and then coming back to a point near the inner edge at the rigid uprights, a truss is formed which holds the central blocks 65 between two rigid uprights just as firmly against outward movement as it does the blocks adjacent to the uprights. Furthermore, by having these rods embedded in a layer of concrete and placed on a downwardly and outwardly inclined surface, 70 there is no danger of the layer of concrete shearing out at the rods because the thrust against the wall is in a direction straight outwardly, and this thrust causes the horizontal binding wires or rods to bind more firmly against the tops of the layers of tile, 75 thus preventing any possibility of having these rods shear the layer of concrete when subjected to a severe outward thrust.

I claim as my invention:

1. In a wall structure, walls arranged at angles to each other, an upright corner post comprising hollow blocks arranged with their openings vertical, upright posts spaced from said corner post comprising blocks each having a plurality of openings through it, the openings being vertical, upright reinforcing in the openings of the corner post, upright reinforcing in all of the openings of the alternate blocks in said upright post, 85 and extended through the adjacent openings of the other blocks in said upright post, said walls being comprised of blocks having their ends at the inner and outer surfaces of the walls vertical, and having their walls inclined downwardly and outwardly from the inner surface of the wall, reinforcing members arranged between the courses of the blocks in the wall, and connected to said upright reinforcing and curved so that between the posts said horizontal reinforcing, 90 last described, extends toward the outer surface of the wall and at the post extends to points near the inner surface of the wall. 95

2. In a device of the class described, walls arranged substantially at right-angles to each other, a corner post adjacent to said walls, upright posts in said walls spaced from said corner post, said posts comprising hollow blocks having their openings vertical, the walls comprising hollow blocks with their ends vertical, and with their openings inclined downwardly and outwardly, horizontal reinforcing members between the courses of blocks in the walls, arranged with their center members near the outer surface of the wall, and with their end members near the inner surface of the wall, and upright reinforcing members in said posts secured to the ends of said horizontal reinforcing members. 110

Des Moines, Iowa, June 28, 1915.

HALVER R. STRAIGHT.
